UNITED STATES PATENT OFFICE.

JAMES I. CARROLL, OF CINCINNATI, OHIO.

BABY WALKER.

Application filed April 3, 1920. Serial No. 371,044.

To all whom it may concern:

Be it known that I, JAMES I. CARROLL, a citizen of the United States, residing at Cincinnati, in the county of Hamilton and State of Ohio, have invented certain new and useful Improvements in Baby Walkers, of which the following is a specification.

My invention relates to improvements in devices for the care of very young children; its objects being to provide an attractive and amusing means for assisting the child to learn to walk, enabling a desirable freedom of movement of the child from place to place while safely supporting the child without undue hindrance of its movements. A further object is to make such a device as inexpensive as possible while meeting the stated requirements. Other objects will appear in the course of the ensuing description.

I attain these objects by the device illustrated, for example, in the accompanying drawing, in which—

Figure 1 is a perspective view of the device in use;

Fig. 2 is a similar view of the device without the child thereon;

Fig. 3 is a perspective view of the device as it is disassembled and packed for storage and distribution, with an enclosing box or the like represented by broken lines;

Fig. 4 is a vertical longitudinal section on a plane corresponding to the line 4—4 of Fig. 2;

Fig. 5 is a front elevation of the device; and

Fig. 6 is a perspective view, corresponding to Fig. 2, but showing the device modified in certain parts.

As I prefer to construct my invention, it comprises a bed 1 of flat elongated shape with a wide major rear part forming the seat 2 and a wide minor front part forming a bolster support 3, with an intermediate narrower connecting part 4, into which the seat 2 and bolster support 3 merge in smoothly curved edges. Also, preferably, the corners of the seat 2 at the rear and the corners of the part 3 at the front are suitably rounded.

The rear bolster 5 has its bottom straight and its middle part has a flat top against the bottom of the bed 1 close to the rear end of the latter, secured thereto by screws 6 passed down from the top of the bed. From this flat top, the bolster 5 curves down to thinner end parts 7. An axle 8 is nailed to the flat bottom of the bolster 5, with its ends 9 pro-

jected past the respective ends of the bolster, and rear wheels 10 turn loosely on these projections, held thereon by pins 11 through openings in the projections. 60

The front bolster 12 has its top wide and flat, against the bottom of the part 3 of the bed 1, a short distance back from the front end of the latter, secured thereto by screws 13 passed down from the top of the bed. 65 This front bolster, or pedestal, 12 has its lateral ends converged downward, leaving a narrow bottom; and a bore 14, up into the bolster or pedestal, receives the socket 15 in which is held the caster 16 by the stem of 70 the latter extending up into the socket and having the stem-head 17 engaging above the upper end of the socket by virtue of resiliency of the socket material, as with any suitable well known furniture caster. Also, 75 preferably, this caster 16 has ball-bearings 18, such casters being readily obtainable on the market.

The converged lateral ends of the bolster or pedestal 12 have bores in which tightly fit outriggers 19, each composed of a round strip such as an ordinary dowel rod, and inclining downwardly and laterally outwardly to about the front-to-rear line of the respective rear wheel 10 (Fig. 5,) and each outrigger 19 preferably has its lower end 20 beveled to be about parallel with the floor or other level surface on which the vehicle rests. Moreover, these lower ends 20 are short distances up from that surface, as 90 shown.

In the modification of Fig. 6, instead of the bolster or pedestal 12 with its outriggers 19, there is a front bolster 12' with wheels 10', like the rear bolster 5' and wheels 10; the bolster 12' being screwed to the bed by the screws 13, the same as the bolster or pedestal 12 in the preferred example. Another variation here shown is the skein 8' for each front or rear wheel 10' or 10, integral with the respective bolster 12' or 5', with a shoulder 7' between which and the pin 11 the wheel is held to turn loosely. 95 100

As shown in Figs. 1 to 5 inclusive, the superstructure comprises front and rear posts 21 and 22, rectangular in cross-section except near their lower ends, where they have integral rounded shanks 23 and 24 respectively. The bed 1 has a bore 25 near the forward end of the narrower connecting part 4, in the middle of the bed; and has another bore 26 just forwardly of the rear 105 110

bolster 5 in median alinement with the front bore 25. The front and rear posts 21 and 22 have their shanks 23 and 24 extending down through the bores 25 and 26, respectively, with pins 27 through them where they project below the bottom of the bed 1, holding the posts firmly with the shoulders 23' and 24' of the posts 21 and 22, respectively, resting firmly down against the top 10 surface of the bed 1. A ring 28, preferably of heavy wire welded or soldered at its ends to make the ring smooth and continuous, passes through transverse openings 29 and 30 through the respective posts 21 and 22 15 near their tops.

In the modification of Fig. 6, the posts 21' and 22' are fitted to the bed as in the preferred example; but instead of the upper openings 29 and 30, with the ring 28 20 therein, two straps 31, of leather or webbing, or other suitable flexible but strong material, are riveted together at both ends, with ample lengths of their end parts mutually overlapping, and with intermediate 25 stretches 32 left unriveted and separated and receiving between the separated stretches 32 the upper end parts of the respective posts 21' and 22', to which the stretches 32 are tacked or nailed.

30 The support made up of the posts and ring, or otherwise constructed to encircle the child's body above its waist line while the child is seated astraddle of the narrower bed part 4, upon the wider bed part 35 2, confines the child to the device; yet as this is the only encircling means, there is no hampering of the legs and arms, and no hindrance to close approach of the infant, with the device, to objects that may attract 40 its attention. This contributes better to the child's amusement than a device having much laterally extended structure lower down, as in various baby walkers heretofore disclosed.

45 In either example, the device may be partially disassembled by removing the posts 21 and 22 or 21' and 22' from the bores 25 and 26; and then these posts may be folded toward each other across the encircling element 28 or 31. The other part of the de-

vice, inverted in a suitable box, carton, wrapper or other suitable container A, indicated by the dotted lines in Fig. 3, may receive the flat folded superstructure on the bottom of the bed 1 between the rear 55 and front bolsters.

Modifications of materials or of details other than herein disclosed are possible. Therefore, I do not wish to be understood as being limited to such precise showing 60 and description, but having thus fully described my invention,

What I claim as new and desire to secure by Letters Patent is:

1. In a baby walker, a structure comprising a seat entirely open at its sides, and a body-support to flank the body of a child, exclusively above the child's waist-line and closely enough to prevent escape of the child at either open side of said seat, when seated on said seat astraddle of said structure, and rolling means supporting said structure for propulsion of the device by contact of the child's feet with a surface supporting said rolling means. 65

2. In a baby walker, a rear rolling support, a front rolling support, a rigid element rigidly connecting said supports along the front-to-rear central line of the device and having a seating surface near the rear support, body-encircling means, and sustaining elements connected to said body-encircling means and connected to said rigid element respectively to the rear of and in front of said seating surface. 80

3. In a baby walker, a structure comprising a seat to support a child astraddle of said structure, rear rolling means and front rolling means supporting said structure for propulsion of the device by contact of the child's feet with a surface supporting said rolling means, said front rolling means being confined close to the front-to-rear center line of said device, for ease of guiding the device, and extensions at opposite sides 90 of said structure to engage said surface forwardly of the rearmost limit of said front rolling means, upon tilting of the device toward the respective side. 95

JAMES I. CARROLL.
